TYPOGRAPHICAL MATRIX

Herman R. Freund, Brooklyn, N. Y., assignor to
 Intertype Corporation, Brooklyn, N. Y., a corporation of New York

Application July 8, 1937, Serial No. 152,643

7 Claims. (Cl. 199—49)

The present invention relates to improvements in typographical machines and more particularly those of the general class described in U. S. Letters Patent No. 436,532 granted September 16, 1890, wherein character bearing matrices released from suitable storage magazines are assembled into lines and while sustained in a so-called "first elevator" are presented to a slotted mold by descent of such elevator to the proper level to aline the matrix characters with the mold slot, after which molten metal is injected at the rear of the mold slot to cast a character bearing slug, the elevator subsequently rising to a position for removal of the matrix line and distribution of the matrices to their proper places of storage.

The present invention relates more particularly to improvements which increase the number of type faces available without the necessity of providing additional matrix fonts, and to this end the invention provides a three-letter matrix capable of use in the machines heretofore adapted to handle only the ordinary one- and two-letter matrices.

The advantages of three-letter matrices have long been recognized, the additional or third type face avoiding the expense and the disadvantages of handling extra magazines and fonts of matrices. However, as heretofore proposed, the locations or datum line positions chosen for three characters on such matrices have not been suitable for alinement of the characters with standard molds which are constructed on the basis of the established alining system for one or two character matrices or for their presentation in proper alinement with the special molds they require except by extensive alteration of the first elevator and other parts of the machine the co-ordination of which is essential to effect alinement. Thus, in every instance, previously proposed, efforts have been directed solely to providing three characters of maximum size located on datum lines equally spaced apart. Such location of the datum lines of the matrix characters, however, does not conform to the established mold alining system; that is, when the lower matrix ears of such three-letter matrices cooperate with the alining surfaces on standard molds, such cooperation being the well known manner of effecting alinement in these machines, the datum lines of none of the characters will coincide with the lower face or surface of the mold slot which constitutes the datum line of the mold.

The present invention provides a novel three-letter matrix wherein the three letters are located

on the same casting edge and are so arranged as to provide three letters of the maximum size possible without departing from the standard mold and character alinement conditions common to the one and two letter matrices. Thus, the three letters are so located on the matrix edge that, as ordinarily, the respective letters of one pair (up to 14 points in size) can be alined individually or can be used selectively, as for mixed composition, with any of the standard molds employed with ordinary two-letter matrices of corresponding point size, while the respective letters of another pair, one up to 14 points in size and belonging to the first pair and the other up to 8 points in size, can be alined individually with another standard mold commonly employed with one-letter matrices.

More specifically, the invention provides a three-letter matrix of standard form and size, with the characters inverted for top alinement as usual, in which two of the characters, up to 14 points in size, are located on the normal lower and upper datum lines in conformity with the established standard for two-letter matrices, while the third character, up to 8 points in size, is located on a certain higher and abnormal datum line in conformity with the established standard for the largest one-letter matrices, such as 42 to 60 point headletter matrices or two-letter matrices up to 24 points, which requires that all three datum lines be not equally spaced apart.

The improved matrix provided according to the present invention, wherein all three characters are located in conformity with the established alining system of standard molds, enables the benefits of three-letter matrices to be obtained in a practical manner, the only limitation being that of size of the third character which cannot extend to the full 14 points in height like the two normally located characters.

To these and other ends, the invention consists in certain improvements and combinations and arrangements of parts, all as will be hereinafter more fully described, the features of novelty being pointed out particularly in the claims at the end of this specification.

In the accompanying drawing:—
 Fig. 1 is a side elevation of a matrix according to the present invention;

Fig. 2 is a vertical section through a standard mold as employed with two-letter matrices and a portion of the first elevator, showing a matrix according to the present invention with its upper character alined with the casting slot, this char-

acter being located on the normal lower alinement datum line;

Fig. 3 is a view similar to Fig. 2, but shows the middle character of the matrix according to the present invention alined with the casting slot, this character being located on the normal upper alinement datum line;

Fig. 4 is a vertical section through a standard mold as employed with one-letter 42 to 60 point matrices, and through a portion of the first elevator, showing the matrix according to the present invention with its lowermost character alined with the mold slot, this character being located on the lowest possible datum line which is known as the headletter alinement position;

Fig. 5 is a view similar to Fig. 4, but shows the uppermost character on the matrix according to the present invention alined with the casting slot of the mold; and

Fig. 6 is a collective view showing in side elevation the several forms of one- and two-letter matrices all having their characters located at normal datum line positions in conformity with the established standards of mold and matrix alinement, this figure also showing a three-letter matrix according to the present invention having its characters located in conformity with such normal datum line positions.

Similar parts are designated by the same reference characters in the several figures.

The novel three-letter matrix provided by the present invention is adapted to be used in typographical machines of well-known construction provided with a matrix line transporter 1, usually termed the "first elevator", having front and back jaws 2 and 3 to receive the matrix lines, said elevator being mounted to move vertically as usual on a vise frame the cap 4 of which is provided with a so-called alining bar 5 with which a screw 6 on the head of the first elevator is adapted to cooperate. The alining bar is provided with a pair of stop pins 7 and 8 of appropriate heights, and when the first elevator descends to lower a matrix line into casting position in front of the mold, the screw 6 may come to rest either directly on the alining bar 5 as shown in Figs. 2 and 5, or on the stop pin 7 as shown in Fig. 3, or on the stop pin 8 as shown in Fig. 4, thus positioning the matrix line for alinement at the lower or normal alinement position corresponding to the datum line X—X for the tops of the upper characters on the usual two-letter matrices, or at the upper alinement position corresponding to the datum line Y—Y for the tops of the lower characters on the usual two-letter matrices, or at the so-called high or headletter alinement position corresponding to the datum line Z—Z for the tops of characters of large point size on single letter matrices. These three alinement positions are in accordance with long established standards, and since the means provided in the machines for stopping the first elevator at one or another of these positions is well known, further illustration and description thereof are deemed unnecessary.

Referring more particularly to Fig. 1, the matrix M provided by the present invention is of the usual form and size employed in typographical machines of the class hereinbefore referred to, it having upper and lower ears 10 and 11 projecting from its front and rear edges respectively and being provided in its casting edge 12 with three letters or characters. The two characters 13 and 14 are punched at the usual vertical positions and ordinarily do not exceed

14 points in vertical height, the characters being inverted in the usual manner for top alinement. The vertical positions of these two characters conform to a long established standard for the ordinary two-letter matrices M' (Fig. 6), the tops of the respective characters, regardless of their height, alining on one or the other of the datum lines X—X or Y—Y, Fig. 6, these lines being commonly referred to as the lower or normal and upper or roman and italic alinement positions respectively.

The matrix according to the present invention is provided with a third character 15 which is located on a datum line Z—Z of the matrix M² (Fig. 6), which is commonly termed the high or headletter alinement position. This latter position is also in conformity with a long established standard for single letter matrices of large point size, such as 42 to 60 point headletters.

More recently, there has been developed a two-letter matrix for characters of larger point size than the former 14-point limit, and by locating the top of the character in the upper alinement position, such as the lower character on the matrix M³ (Fig. 6), on the datum line Z—Z, and the top of the character in the lower alinement position on such a matrix on the datum line X—X, it was found possible to provide two characters of the maximum point size possible (24 points) to fit within the casting edge of the standard matrix.

The datum lines X—X, Y—Y and Z—Z are not equally spaced apart, as will be observed from Fig. 6, and this unequal spacing of the datum lines is an important factor of the present invention. By referring to the mold 16 shown in Figs. 2 and 3, it will be observed that it is provided with lower and upper alining rails 17 and 18 respectively, these rails engaging over the top of the lower rear ears 11 of the matrices at the proper time to effect horizontal alinement of the respective matrix characters with the casting slot in the mold, in the manner usual and well known in machines of this class. Since the characters 13 and 14 of the matrix M according to the present invention are located in conformity with the established two-letter matrix and mold alinement system, it will be evident that the alinement of either of these characters will depend upon presentation of the matrix for engagement with either rail 17 or rail 18. The characters 13 and 14 thus constitute a pair of characters which can be alined individually in front of the mold slot or, as in mixed composition, some of the matrices in an assembled line may have the character 13 alined with the mold slot while other matrices in the line have the character 14 alined therewith.

The mold 16a shown in Figs. 4 and 5 is provided with lower and upper alining rails 19 and 20 respectively, the rail 19 being located at the same distance from the datum line 21a (which is coincident with the lower casting face of the mold slot) as the rail 17 on the mold 16 in Figs. 2 and 3 is located from the corresponding datum line 21. The rail 20, however, is located much closer to the datum line 21a of the mold 16a than is the rail 18 with respect to the datum line 21 of the mold 16 shown in Figs. 2 and 3, the rail 20 corresponding to the high or headletter alinement position for one-letter matrices up to the largest point size possible, namely 60 points, as for example is represented by the matrix M² in Fig. 6. Consequently, when the matrices M according to the present invention are presented to

the mold shown in Fig. 4 with their lower rear ears engaged against the underside of the rail 20, the character 15 on such matrices will aline with the mold slot, since the datum line Z—Z on which the character 15 is located coincides with the datum line 21a of the mold; and when matrices according to the present invention are presented to the mold with their lower rear ears engaged against the underside of the rail 19 on the mold 16a, as in Fig. 5, such matrices being then presented in the lower alinement position, the characters 13 located on the normal datum line X—X will be alined with the mold slot, this datum line being then coincident with the datum line of the mold.

Since the datum lines of the characters on the matrices provided by the present invention are in conformity with the long established or standard mold alinement levels and the levels to which the matrix lines are lowered to casting position by the line transporter or first elevator in machines of this class as generally constructed, the improved matrices are usable in such machines without requiring any special construction thereof, and without impairing the usefulness of such machines for composition using the usual matrices. The two forms of standard molds employed with the improved three-letter matrices may obviously be mounted on the same mold disk commonly employed in machines of this class, so that one or the other mold may be readily brought into use in the usual and well known way for cooperation with the improved matrices for casting from one or the other of the upper pair of characters, or for casting from the third or lowermost character.

I claim as my invention:

1. A matrix for use in a typographical machine having slug casting means presenting a constant datum line and means for alining matrices at different unequally spaced heights relatively to said datum line, said matrix having type forming characters thereon the datum lines of which are located at different unequally spaced heights corresponding respectively to the heights at which the matrices are alined by said alining means.

2. A matrix for use in a typographical machine provided with a matrix line transporter having means for positioning a matrix line in three unequally spaced alining positions, said matrix having type forming characters thereon the datum lines of which are located at different unequally spaced heights corresponding respectively to said alining positions of the line transporter.

3. A matrix for use in a typographical machine provided with slug casting means presenting a constant datum line and means for alining matrices at different unequally spaced heights relatively to said datum line, and a line transporter having means for positioning a ma-

trix line at three alining positions corresponding to the heights at which the matrices are alined by the alining means, said matrix having type forming characters thereon the datum lines of which are located at different unequally spaced heights corresponding to the respective heights at which the matrices are positioned by the line transporter and alined by the alining means.

4. In a typographical machine, the combination of mold means having a constant datum line 10 and means for alining matrices at three different unequally spaced levels relatively thereto, a line transporter having means for positioning matrices at three unequally spaced heights corresponding to said alining levels, and matrices 15 each having in its casting edge three type forming characters the datum lines of which are located at heights corresponding to the respective heights at which matrices are positioned by the line transporter and alined by the alining means. 20

5. In a typographical machine, the combination of a slug casting mold having means for alining matrices therewith at the usual lower and upper levels and a slug casting mold having means for alining matrices therewith at the usual lower level and at a high level above said upper level and at a different distance from said upper level than the distance of said upper level from the lower level, the datum lines of said molds being coincident, and matrices each provided in its casting edge with three type forming characters the datum lines of which are located at heights corresponding respectively with said lower, upper and high alinement levels. 30

6. In a typographical machine, the combination of a slug casting mold having rails spaced from its datum line to aline matrices at the usual lower and upper levels and a slug casting mold having rails spaced from its datum line to aline matrices at said lower level and at a high level 40 above said upper level and at a distance from said upper level less than the distance of said upper level from said lower level, the datum lines of said molds being coincident, and matrices each provided in its casting edge with three type forming 45 characters located at different unequally spaced heights corresponding respectively with said lower, upper and high alinement levels.

7. A matrix for use in a typographical machine provided with at least two slug casting 50 molds having coincident datum lines and means for alining matrices at two different levels with respect to said datum line, said matrix having three type forming characters unequally spaced apart on an edge thereof, the upper of which 55 characters is located for alinement with the datum line by the alining means on both of said molds and the other two of which characters are located for alinement with the datum line by the alining means on one only of said molds. 60

HERMAN R. FREUND.
